UNITED STATES PATENT OFFICE.

WILLIAM M. HORNBECK, OF TOPEKA, KANSAS.

AUTOMATIC STOCK-FEEDER.

1,121,502.

Specification of Letters Patent. Patented Dec. 15, 1914.

Application filed July 18, 1910. Serial No. 572,470.

To all whom it may concern:

Be it known that I, WILLIAM M. HORNBECK, a citizen of the United States, and a resident of the city of Topeka, in the county 5 of Shawnee and State of Kansas, have invented a new and useful Improvement in Automatic Stock-Feeders, of which the following is a specification.

This invention relates to new and useful 10 improvements in automatic stock feeders and comprises a simple and efficient apparatus of this nature having various details of construction, combinations and arrangements of parts which will be hereinafter 15 fully described, shown in the accompanying drawings and then specifically defined in the appended claim.

In the drawings accompanying and forming part of this specification, and in the 20 description of the drawings, I have shown my invention in its preferred form, and have shown what I deem to be the best mode of applying the principles thereof, but it is to be understood that I contemplate changes 25 in form, proportions, and materials, the transposition of parts, and the substitution of equivalent members, without departing from the spirit of my invention.

Figure 1 is a perspective view of an automatic stock feeder made in accordance with the principles of my invention, the same being accessible by all sizes of stock. Fig. 2 is a view of the same with the removable and attachable fence applied there- 35 to, and the adjustable gate in place so as to give the smaller sizes of stock access to the main portion (for instance, to the portion holding the grain), and all sizes of stock access to the remaining portion (for in- 40 stance, the portion holding the medicine). Fig. 3 is a top view of the gate and adja- 45 cent portions of the fence. Figs. 4 and 5 are sections giving the details of the brackets for removably attaching the fence onto the platform. Fig. 6 is a sectional elevation of the bin and troughs and the force feed and regulating device. Fig. 7 is in 50 part an elevation, certain portions being removed or broken away, to show especially the partitions, and the force feed. Fig. 8 is a perspective view of my apparatus with 55 a large storage bin applied thereto for holding a large quantity of grain which is automatically discharged into the smaller bin as it is discharged from the smaller bin through the force feed.

Similar reference characters indicate like or corresponding parts throughout the several views.

The base of my apparatus comprises the 60 two end-pieces 10, 10, between which are formed the two troughs 11, 11, by means of the outside strips 12, 12, and the two inside pieces 13, 13 which come up to a point along the middle line of the machine. 65 Besides being properly nailed or screwed or bolted together in any suitable manner, the frame is held rigidly together by means of the tie-rod 53. Above this base with the two troughs is erected a bin or hopper-like 70 reservoir 14, with a door 15 giving access thereto for discharging the grain thereinto. It is provided with substantially vertical sides 16, 16 which extend down toward the 75 respective pieces 13, 13, but leaving a wide gap, so that the grain 17 in the bin is free to run down into the troughs. Preferably, for practical purposes, I partition off one end of the bin by a partition 18, using the 80 larger compartment for grain and the smaller compartment for medicine or otherwise treated food, and the troughs are correspondingly partitioned, as indicated at 19.

In order to regulate the flow of feed into the troughs, so that the same machine may 85 be made applicable to various circumstances, such as for different feeds, for different stock, and for different atmospheres (as to humidity especially), I adjustably secure to each side piece an adjusting door 20, 90 which may be slipped up and down thereon, so as to increase or diminish the size of the opening through which the grain is discharged; the door being secured in any position by means of the bolts and thumb-nuts 95 22 which engage in the slots 21 in the door. Inasmuch, however, as all or most all feed will pack or clog, especially in an opening which is not apt to discharge too much feed into the troughs, I provide a force-feed, 100 which comprises one or more irregularly shaped devices 25, 25 pivoted to the board 13 at 24 and having an operating lever 26 ex- 105 tending down and terminating in the bottom of the trough; and preferably the end is in the shape of a ring or is otherwise suitable shaped or enlarged so as to be operable by the feeding animal's nose. Each of these devices is adapted to rock or oscillate on the pivot, its movements being limited by the 110 stop-pins 27, 27. The manner of operating this force-feed is as follows: When the feed-

ing animal has consumed all the grain in the trough which is easily accessible it will try to get that under or adjacent to the operating handle, and in so doing will push the handle from one side to the other; and this 5 rocking or moving of the force-feeding device in the opening will force more feed into the trough or agitate it so that it will run down by force of gravity. Naturally, however, 10 the animal will not try to get the grain under the handle until the grain more easily accessible is consumed, so the force-feed will naturally not be operated until nearly all the grain in the trough is eaten. The liability 15 of overflowing the trough and wasting the grain is thus eliminated and at the same time an ample supply for the hungry animal is assured.

30 is a platform on which I prefer to place my machine to keep it out of the dirt. The platform is preferable set on runners 31 and hooks or clevises 31', so that it may be easily drawn from place to place over the ground. It is also preferably provided at 25 each end with a run-way 32 hinged thereto so as to give the smaller stock, as pigs, free access to the feeding troughs. When drawing the platform over the ground the run-ways may be turned up or over on their 30 hinges and secured in any suitable manner.

In order that only stock of a certain size may have access to the grain, while all stock has access to the medicine in the smaller compartment, I provide a fence having the 35 sides 33 and 34, and the end-gate 37. The side 33 may be removably secured to the platform by means of the brackets 34' and lag-screws 35, 35, and the side-piece 34 may be secured by means of the straps 36 and 40 screws 35, 35. The gate is slidable vertically in the ways 38, 38, and is vertically adjustable and secured at any desired height above the platform by means of the hand-bolts 40, 40 which engage in holes in the brackets 39, 45 39, respectively. And to hold the fence and gate rigidly together, I insert a tie-rod 41 from side to side. This fence and gate ar-

rangement is especially desirable when feeding young pigs; as the pigs have access at all times to the grain which is provided especially for them, while all of the stock has at all times free access to the medicine or treated feed.

To provide a means for keeping a larger constant supply of feed, so it will not be necessary to personally attend to the filling of the bin so frequently, I provide a larger hopper-like reservoir 60, set upon studs 61 and runners 62, and provided with a spout 63 which passes through the roof of the 60 smaller bin. This spout may be telescoped upwardly to remove it from said hole so as to permit either part of the apparatus to be pulled away. The larger bin may be provided with a door 64 through which it may be filled. Obviously, as the grain in the smaller bin is discharged below the spout, grain from the upper bin will flow down through the spout into the smaller bin; and equally obvious is it that by having the 70 lower end of the spout below the door 15, the grain will not overflow the lower bin.

Extending across the trough lengthwise is a bar 50, and a series of straps 51, 51 span the trough from the bar to the outer edge 75 of the trough to keep the stock out of the trough.

22 is a strap iron to protect the edge of the trough.

What I claim is:

In combination, a frame having a hopper-like bin, a feeding trough under the bin, and an opening from the bin into the trough, a larger storage bin mounted on runners and supported thereon above the first-named bin, 85 and a spout extending from the larger bin down into the first-named bin.

In testimony whereof, I have hereunto signed my name in the presence of witnesses.

WILLIAM M. HORNBECK.

Witnesses:

LAURA L. HORNBECK,

J. M. STARK.
